United States Patent

Des. 239,896
Patented May 18, 1976

239,896

COMBINED ART TOOL CADDY AND REMOVABLE HANDLE THEREFOR

Dallas R. Bottcher, 911 Cobblestone Drive,
Lincoln, Nebr. 68510

Filed June 13, 1974, Ser. No. 478,908

Term of patent 14 years

Int. Cl. D6—04

U.S. Cl. D6—189

FIG. 3

FIG. 4

FIG. 1 is an exploded perspective view of a combined art tool caddy and removable handle therefor showing my new design including a removable handle and top insertion piece;

FIG. 2 is a rear view thereof;

FIG. 3 is a bottom view thereof; and

FIG. 4 is a perspective view thereof in fully assembled position.

I claim:

The ornamental design for a combined art tool caddy and removable handle therefor, substantially as shown.
